UNITED STATES PATENT OFFICE.

EDWARD C. ROSS, OF NEWBURG, NEW YORK.

DESIGN FOR A RADIATOR.

SPECIFICATION forming part of Design No. 29,551, dated October 25, 1898.

Application filed September 28, 1898. Serial No. 692,135. Term of patent 7 years.

To all whom it may concern:

Be it known that I, EDWARD C. ROSS, a citizen of the United States, residing at Newburg, in the county of Orange and State of New York, have invented and produced a new and original Design for Radiators; and I do hereby declare the following to be a full, clear, and exact description of the same, reference being had to the accompanying drawing, forming a part thereof.

The distinctive features of my design are hereinafter more particularly described, and consist in certain details of the outward configuration of the top and bottom and of the connecting tubes or columns.

The top A and bottom B of the radiator are counterparts one of the other, save that the bottom B has attached thereto the legs b.

The ends of those parts of the radiator

nearest the center of the design are of greater 20 diameter than the outer ends, making the connecting sides *a* inclined, as shown. The larger ends of these portions are also provided around the outside of these larger ends with the oval bead *c*. Each of the columns C is 25 provided at each end with a semicircular bead *c'*, near the inner heads of the top and bottom.

What I claim, and desire to secure by Letters Patent, is—

The design for a radiator, substantially as 30 described and shown.

In testimony whereof I affix my signature in presence of two witnesses.

EDWARD C. ROSS.
